UNITED STATES PATENT OFFICE.

MAX HASAIT, OF DRESDEN, GERMANY, ASSIGNOR TO AKTIEBOLAGET ARS, OF STOCKHOLM, SWEDEN, A CORPORATION.

TRACK RAIL FOR CURVED STAGE SCENES.

Application filed January 27, 1922. Serial No. 532,328.

To all whom it may concern:

Be it known that I, MAX HASAIT, citizen of Germany, residing at Dresden, Germany, have invented certain new and useful Improvements in Track Rails for Curved Stage Scenes, of which the following is a specification.

This invention relates to a track rail for curtains or screens in theatres, cinematograph halls or the like, adapted to be illuminated by reflectors or projecting apparatus of any kind, and which must present a surface free from folds or creases. An object of the invention is to obtain a noiseless winding and unwinding of the scenes or curtains, while at the same time the formation of folds thereon is impossible.

Another object consists in arranging the track rail in such manner that parts of the scenery or the theatre machinery in general may be introduced or moved within the space occupied by said track rail. To this end the supporting machinery or track rails is wholly or partly mounted in an adjustable manner in all directions, for instance it may be wholly or partly raised or dropped towards the floor of the stage or removed altogether from the stage. At the same time the ropes, leather straps, chains or the like provided in the track rail and effecting the movements of the scenes or curtains are so arranged that they may remain in the rail during the adjustment, raising or dropping of the same. Besides, two or more track rails may be placed at different distances from the stage opening and adjustable in such manner, that the curtain or screen may be drawn forward upon a greater or smaller depth of stage.

The adjustment of the track rail may be effected by any means, for instance the rail may be provided at suitable points with hinges or the like so located that the rear portion of the rail in the form of half an ellipse may be dropped into a vertical position, the space occupied by said portion being accessible for other parts of the theatre machinery.

The ropes, leather straps, chains or the like may be retained in the track rail during the adjustment of the same by the ropes or the like being provided at suitable points with joints adapted to be undone by means of rope joints.

The invention is illustrated in the accompanying drawings in which—

Fig. I is a front elevation of a track rail constructed according to the invention. Fig. II is a plan thereof. Fig. III is a cross-section of the track rail to a greater scale. Fig. IV illustrates a side view in section on line C—D in Fig. V of a modified form of the invention comprising two track rails, one located behind the other. Fig. V represents a plan view of this modified form. Figs. VI and VII show to a greater scale and in different positions mechanisms for operating parts of the track rail. Figs. VIII is a plan view thereof. Figs. IX and X illustrate a side view and a plan view respectively of still another embodiment of the invention. Figs. XI and XII are detail views.

Referring to Figs. I to III the track rail comprises a curved portion somewhat in the form of half an ellipse, and two straight shanks. By means of adjustable suspension rods *a* the rail is suspended from the ceiling *b* of the stage in such a manner that the rail slopes a little towards the back wall *c* of the stage, which the audience faces. By means of stay rods *d* the rail is connected with the back wall *c* which therefore receives the tensile stresses of the rope effecting the movements of the curtain or screen. Said rope runs in a longitudinal channel *e* in the track rail, and is directly supported in the channel without the provision of special supporting means such as rollers or the like. The curtain or screen directly fixed to the rope hangs down through the longitudinal slot *f* of the track rail to the floor of the stage. Owing to the downwardly inclining position of the rail the curtain is stretched by gravity so as to form a surface without folds. The rope of the curtain is considerably longer than the latter. The end of the rope where the curtain commences is attached to a conical drum *g* which may rotate about a vertical axis and in the known manner be moved axially a distance corresponding to the thickness of the rope for each revolution of the drum. The shank of the track rail directed towards the said drum is movable horizontally about a hinge *h* and is moved for instance by means of a gear connected with the shaft in the known manner automatically in correspondence to the slope of the side surface of the drum *g*,

so as to cause the track rope to be wound and unwound in a correct manner. The other end of the rope passes over a roller *i* to a drum *k*. By turning this drum the curtain is unwound from the drum *g* and drawn into the track rail. By turning the drum *g* the curtain is again pulled out of the track rail and wound on to the latter drum.

10 In the modified form of the invention shown in Figs. IV and V the ellipse-shaped portion of the track rail may be raised and lowered so as to allow parts of the scenery or the machinery to be introduced and moved within the space occupied of said ellipse-shaped portions.

Besides, said figures illustrate the use of two different track rails, one *A* placed nearer the stage opening than the other one *B*.

20 1 is the conical drum onto which the rope, leather strap, chain or the like actuating the curtain or screen is wound, and 2 is the floor of the upper machinery. The front track rail *A* is provided with hinges 3 and 4 by means of which the ellipse-shaped portion of said track-rail may be lowered to the vertical position indicated in Fig. IV by dotted lines and raised to the position shown in full drawn lines. The raising and lowering of said track rail portion is effected by the aid of a windlass 5 placed on the floor 2 and connected at the points 7, 8 and 10 with the movable track rail portion by ropes 6. The rope 7 actuating the scenes or curtains passes from the drum 1 through the track rail *A* and round a guiding roller 8 to a winding drum 9. A similar movement of the ellipse-shaped portion of the rear track rail *B* may be effected by means of hinges 11, 12, a windlass 13 and ropes 15. After the ellipse-shaped portions have been lowered, the ropes 6 or 15 are lowered to the stage floor and the rope joints connecting the same with said portions are disconnected, whereupon the ropes 45 are hoisted up to the upper machinery. The rope 16 actuating the curtain or screen, when connected with track rail *B*, passes from the drum 1 through said track rail and round rollers 17 to the winding drum 18.

50 In Fig. V the track rails are so positioned that the curtain or screen passes through the rear track rail *B* by means of the rope 16. If the scenes are to be passed through the fore track rail *A*, this is effected in the following manner illustrated in Figs. VI, VII and VIII.

First the curtain is wound onto the conical drum 1 and then the joint 21 of rope 16 is disconnected and the joint 22 of rope 7 connected with the part of the rope wound onto the drum 1. Then the curtain is passed through the track rail *A* by turning the drum 9. Before passing the curtain through said track rail *A* the shanks 19 and 20 of the track rails have to be moved in the direction

of the arrow in Fig. V. This is effected by the aid of a crank 23, the shaft 24 of which is threaded and engages corresponding adjustable nuts connected with the shanks 19 and 20, said shanks being connected with the remaining portions of the track rails *A* and *B* respectively by hinges 25.

As stated above the ropes passing through the track rails may remain in the same during the lowering of the ellipse-shaped portion of the track rails. This is effected by the following means, shown in Figs. VI, VII and VIII. The hinge 11 of the track rail is connected with a sliding piece 26 adapted to slide up and down in a stay 27 which is attached to the bottom 2 and actuated by a screw-spindle 28 provided with a hand-wheel 29. By this means the hinge 11 can be raised and lowered. The fore part 20 of the track rail may be moved towards the 85 conical drum 1 by means of a screw spindle 30 journalled in bearings 31 and 32 and engaging a bearing 34 secured to part 20, so as to bring about an interspace between the adjacent ends of part 20 and the ellipse-shaped 90 part, as will appear from Fig. VII. Before lowering the last-named part, the rope 16 should be slackened which is effected by turning the drum 1. The part 20 is adapted to slide in relation to the bearing 24 engaging the screw-spindle 24.

If the ellipse-shaped parts of track rails *A* and *B* are to be lowered or raised about the points 10 and 33 in Fig. V, these points should be provided with hinges similar to the 100 hinges 3, 4, 11 and 12, and in this case the ropes 6 and 15 in Figs. 1 and 2 are to be connected with the track rails in the points 3, 4, 7, 8 and 11, 12, 35, 36 respectively. Also in this case the mechanism 30, 31, 32, 105 34 is to be used and disconnectible rope joints to be inserted in the ropes 7 and 16 at points where they are needed.

If the ellipse-shaped parts of the track rails are to be removed altogether, the hinges 110 3, 4, 11 and 12 should be provided with removable hinge-bolts.

If desired, the curtain or screen can be placed at varying distance from the stage-opening, while using a single track-rail. 115 This is effected by the means illustrated in Figs. IX, X, XI and XII.

The ellipse-shaped part of the track rail is suspended from a carriage by means of adjustable hangers 37, 38, 39, 40, 41, 42 and 120 43. The carriage consists of four frameworks 44, 45, 46 and 47 adapted to travel by means of rollers on guiding bars 48 and 49. The carriage is actuated by a motor or by the hand, as for instance by windlasses 125 50, 51 and ropes 52, 53. The straight parts of the track-rail is suspended from ropes 54, 55, 56, 57 adapted to be wound onto rollers 58 and 59 and raised or lowered by means of the same. Said parts of the track rail 130

may be of varying length so as to be adjusted to the varying distance of the curtain or screen from the stage opening. The said straight parts are open at the top, as shown

5 by 60 in Fig. XI, in order that the rope may be easily inserted in the track-rail from the conical drum 1 and then by means of rope joints connected with the rope passing through the ellipse-shaped part. The different parts of the track rail are connected 10 by the aid of hooks 61, Fig. XII and pins 62, Fig. XI.

What I claim as new and desire to secure by Letters Patent of the United States is:—

15 1. A track rail for curved stage scenes, comprising a curved back portion of the track rail substantially in the form of half an ellipse, extending across the stage, the track rail being located in a downward sloping plane, means for supporting and moving the scenes lengthwise in said track rail, and means engaging the track rail for adjusting the same to any desired position.

20 2. A track rail for curved stage scenes, comprising a curved back portion of the track rail substantially in the form of half an ellipse, extending across the stage, straight fore portions of the track rail, means for supporting and moving the scenes lengthwise in said track rail, and means engaging the track rail for adjusting the same to any desired position.

25 3. A track rail for curved stage scenes, comprising a curved back portion of the track rail substantially in the form of half an ellipse, extending across the stage, the track rail being located in a downward sloping plane, straight fore portions of the track rail, means for supporting and moving the scenes lengthwise in said back and fore portions, and means engaging the track rail for adjusting the same to any desired position.

40 4. A track rail for curved stage scenes, comprising a curved back portion of the track rail substantially in the form of half an ellipse, extending across the stage, the track rail being located in a downward sloping plane, straight fore portions of the track rail, traction means adapted to slide in the track rail and supporting the scenes along their whole length, means for moving said traction means, and means engaging the track rail for adjusting the same to any desired position.

45 5. A track rail for curved stage scenes, comprising a curved back portion of the track rail substantially in the form of half an ellipse, extending across the stage, the track rail being located in a downward sloping plane, traction means adapted to slide in the track rail and supporting the scenes along their whole length, a rotary conical drum located near the track rail, the traction means being adapted to be wound and

unwound on the conical surface of said drum, and means engaging the track rail for adjusting the same to any position.

6. A track rail for curved stage scenes, comprising a curved back portion of the track rail substantially in the form of half an ellipse, extending across the stage, the track rail being located in a downward sloping plane, straight fore portions of the track rail, traction means adapted to slide in said back and fore portions, a rotary conical drum located at the end of one straight fore portion, the traction means being adapted to be wound and unwound on the conical surface of said drum, and means engaging the track rail for adjusting the same to any desired position.

7. A track rail for curved stage scenes, comprising a curved back portion of the track rail substantially in the form of half an ellipse, the track rail being located in a downward sloping plane, straight fore portions of the track rail, a rotary conical drum located at the end of one fore portion, the latter being swingable relatively to the drum, traction means supporting the scenes and adapted to slide in the track rail and to be wound and unwound on said drum, and means for adjusting the track rail vertically and horizontally to any position.

8. A track rail for curved stage scenes, comprising a curved back portion of the track rail substantially in the form of half an ellipse, extending across the stage, means for supporting and moving the scenes lengthwise in said track rail, and hoisting means engaging the track rail for raising and lowering any portion of the same towards the floor of the stage.

9. A track rail for curved stage scenes, comprising a curved back portion of the track rail substantially in the form of half an ellipse, extending across the stage, the track rail being located in a downward sloping plane, means for supporting and moving the scenes lengthwise in said track rail, and hoisting means engaging the track rail for raising and lowering any portion of the same towards the floor of the stage.

10. A track rail for curved stage scenes, comprising a curved back portion of the track rail substantially in the form of half an ellipse, extending across the stage, the track rail being located in a downward sloping plane, straight fore portions of the track rail, traction means adapted to slide in the track rail and supporting the scene, means for moving said traction means, and hoisting means engaging the track rail for raising and lowering any portion of the same towards the floor on the stage.

11. A track rail for curved stage scenes, comprising a curved back portion of the track rail substantially in the form of half an ellipse, the track rail being located in a

- 1 downward sloping plane, straight fore portions of the track rail, a rotary conical drum located at the end of one fore portion, the latter being swingable relatively to the 5 drum, traction means adapted to slide in the track rail and supporting the scenes, means for moving said traction means, and means for raising and lowering any portion of the track rail towards the floor of the stage.
- 10 12. A track rail for curved stage scenes, comprising a curved back portion of the track rail substantially in the form of half an ellipse, means for supporting and moving the scenes lengthwise in said track rail, and 15 disconnectible means connecting the said back portion with the remaining parts of the track rail and allowing the removal of the track rail from the stage.
13. A track rail for curved stage scenes, 20 comprising a curved back portion of the track rail substantially in the form of half an ellipse the track rail being located in a downward sloping plane, means for supporting and moving the scenes lengthwise in 25 said track, and disconnectible means connecting the said back portion with the remaining parts of the track rail and allowing the removal of the track rail from the stage.
- 30 14. A track rail for curved stage scenes, comprising a curved back portion of the track rail substantially in the form of half an ellipse, the track rail being located in a downward sloping plane, straight fore portions of the track rail, a conical drum located at the end of one fore portion, means for allowing swinging sideways of the latter relatively to the drum, traction means adapted to slide in the track rail and supporting the scenes, means for moving said traction means and means for raising and lowering any portion of the track rail towards the floor of the stage.
- 35 15. A track rail for curved stage scenes, 45 comprising a curved back portion of the track rail substantially in the form of half an ellipse, the track rail being located in a downward sloping plane, traction means adapted to slide in the track rail and supporting the scenes, means for moving said traction means, means for adjusting the track rail to any position, and means for allowing said traction means to remain in the track rail during the adjustment of the 55 same.
- 60 16. A track rail for curved stage scenes, comprising a curved back portion of the track rail substantially in the form of half an ellipse, the track rail being located in a downward sloping plane, straight fore portions of the track rail, traction means, adapted to slide in said back and fore portions, a rotary conical drum located at the 65 end of one straight fore portion, the traction means being adapted to be wound and unwound on said drum, means for raising and lowering any portion of the track rail towards the floor of the stage, and means for allowing said traction means to remain in the track rail during the adjustment of the same.
- 70 17. A track rail for curved stage scenes, comprising a curved back portion of the track rail substantially in the form of half an ellipse, means connected with said track rail for supporting and moving the scenes lengthwise in the same, means for raising and lowering any portion of the rail towards the floor of the stage, and means for allowing said raising and lowering means to remain in connection with the track rail during its movements.
- 75 18. In stages, means for placing curved scenes at different distances from the stage opening, comprising several track rails, located at different distances from the scene opening, each having a curved back portion substantially in the form of half an ellipse, extending across the stage, means connected with any track rail for supporting and moving the scenes lengthwise in the track rail, and means for transferring the scenes from one track rail to another.
- 80 85 19. In stages, means for placing curved scenes at different distances from the stage opening, comprising several track rails, located at different distances from the stage opening, each having a curved back portion substantially in the form of half an ellipse, extending across the stage, and each being 90 connected with any track rail for supporting and moving the scenes lengthwise in the track rail, and means for transferring the scenes from one track rail to another.
- 95 100 20. In stages, means for placing curved scenes at different distances from the stage opening, comprising several track rails, located at different distances from the stage opening, each having a curved back portion substantially in the form of half an ellipse, extending across the stage, and each being 105 connected with any track rail for supporting and moving the scenes lengthwise in the track rail, and means for transferring the scenes from one track rail to another.
- 110 115 21. In stages, means for placing curved scenes at different distances from the stage opening, comprising any number of track rails, located at different distances from the 120 scene opening, each having a back portion substantially in the form of half an ellipse, straight fore portions of each rail, a rotary conical drum, located near the track rails, means for swinging sideways straight 125 130

fore portions located near the drum, traction means adapted to slide in the track rails and supporting the scenes, said traction means being adapted to be wound and unwound on said drum, and means for transferring the scenes and traction means from one track rail to another.

22. In stages, means for placing curved scenes at different distances from the stage opening, comprising a track rail having a curved back portion substantially in the form of half an ellipse, means for supporting and moving the scenes lengthwise in said track rail, and means for moving the track rail towards and from the stage opening.

23. A track rail for curved stage scenes, comprising a curved back portion of the track rail substantially in the form of half an ellipse, the track rail being located in a downward sloping plane, means for supporting and moving the scenes lengthwise in said track rail, and means for moving the track rail towards and from the stage opening.

25 24. A track rail for curved stage scenes, comprising a curved back portion of the track rail substantially in the form of half an ellipse, the track rail being located in a downward sloping plane, traction means adapted to slide in the track rail and supporting the scenes, a rotary conical drum located near the track rail, the traction means being adapted to be wound and unwound on said drum, and means for moving the track rail towards and from the stage opening.

25. A track rail for curved stage scenes, comprising a curved back portion of the track rail substantially in the form of half an ellipse, the track rail being located in a downward sloping plane, straight fore portions of the track rail, a rotary conical drum located at the end of one fore portion, the latter being swingable relatively to the drum, traction means supporting the scenes and adapted to slide in the track rail and to be wound and unwound on the drum, and means for moving the track rail towards and from the stage opening.

26. A track rail for curved stage scenes, comprising a curved back portion of the track rail substantially in the form of half an ellipse, the track rail being located in a downward sloping plane, straight fore portions of the track rail having adjustable length, means for raising and lowering such straight fore portions, a rotary conical drum located at the end of one fore portion, the latter being swingable relatively to the drum, traction means supporting the scenes and adapted to slide in the track rail and to be wound and unwound on the drum, and means for moving the track rail towards and from the stage opening.

In testimony whereof I affix my signature in presence of two witnesses.

MAX HASAIT.
